UNITED STATES PATENT OFFICE.

JAMES SCRIPPS BOOTH, OF DETROIT, MICHIGAN.

DESIGN FOR A HOOD FOR AUTOMOBILE BODY FRONTS.

Application filed March 5, 1924. Serial No. 8,829. Term of patent 14 years.

To all whom it may concern:

Be it known that I, JAMES SCRIPPS BOOTH, a citizen of the United States, residing at Detroit, in the county of Wayne and State of Michigan, have invented a new, original, and ornamental Design for a Hood for Automobile Body Fronts, of which the following is a specification, reference being had to the accompanying drawing, forming part thereof.

Fig. 1 is a side elevation of a hood for au-

tomobile body fronts showing in full lines my new design the adjacent parts being shown in dotted lines.

Fig. 2 is a front elevation of the hood for automobile body fronts showing my new design the adjacent parts being also shown in dotted lines.

I claim:

The ornamental design for a hood for automobile body fronts substantially as shown.

JAMES SCRIPPS BOOTH.
